Application August 7, 1933, Serial No. 683,986

5 Claims. (Cl. 91—46)

The invention herein disclosed relates to a method and a machine for applying a coating to articles and comprehends an automatic machine of this character the operation of which may be controlled by a check.

In the copending application, Serial No. 654,188, for "Coating machines" there is disclosed and described a machine for coating golf balls. In the machine therein disclosed, the golf balls are coated by dipping them in to a container 10 of lacquer. For this purpose, there is provided a conveyor having several ball carrying elements each of which is brought successively into position to receive a ball, dipped into a container having a liquid coating material therein and passed over a drier to dry the coating on the surface of the ball. Since the conveyor element is dipped in the coating material with the ball, it is also coated. The coating resulting from successive dippings are cumulative and in time the conveyor elements must be cleaned in order to insure that they will continue to function efficiently.

The present invention includes a method for 25 coating the surface of articles and a machine for carrying out the method in which none of the operative parts is coated with the articles passing through the machine. Other objects of the invention include the production of a coating 30 machine which distributes the coating material more uniformly over the surface of the articles coated, which is less expensive to manufacture, which is provided with a positive check control and which is more satisfactory in operation.

35 In accordance with the method of the invention the surface of an article is coated with a lacquer and the article is rotated while the lacquer is drying to distribute the lacquer over the surface of the article. For carrying out the method 40 there is provided a coating machine which includes a container adapted to hold a liquid coating material. Articles to be coated are immersed in the coating material in the container by being plunged therein. Mechanism operating entirely 45 within the container remove the articles from the container and upon being removed the articles are acted upon by mechanism adapted to distribute the coating material over the surface of the article. The mechanism acting within the 50 coating material container is not successively subjected to the coating material and the air which is necessary in order that a coating be formed thereon.

In one form of a machine which embodies my 55 invention there is a receiver for receiving the

articles to be coated, a coating container having a dipping compartment into which the articles to be coated are plunged, mechanism for rotating the articles after they have been dipped to distribute the coating material over the surface of the article, and mechanism for conveying the coated article to a delivery receptacle. The receiver comprises a hopper into which the articles are placed. An opening through the bottom of the hopper delivers articles placed in the hopper to a receiver casing which has an opening therethrough directly over one end of a chute which delivers an article passing through the opening in the bottom of the casing to the container for the coating material. Communication between the casing and the chute is controlled by a disk having apertures, one of which must be brought into register with the aperture in the bottom of the casing in order for an article to pass into the chute. Movement of the 15 disk to bring an aperture therethrough into register with the opening through the bottom of the casing is effected through a motion transmitting train which is incomplete without a removable link, such for example, as a check or coin.

25 Within the container there is a dipping compartment which forms a guide for the article delivered through the chute. The upper end of this compartment is provided with a movable cover which is moved in timed relation with the 30 control disk in the receiver casing so that it is opened when an article passes into the chute. In the dipping compartment, an arm operates to lift the article out of the compartment. The arm is at all times wholly immersed in the coating material except for a moment each time it raises an article out of the container when the end of the arm extends above the coating material. This short exposure is not sufficient however to dry the coating material on the end of 35 the arm.

40 As the article is lifted out of the container it is grasped between a pair of journaled prongs which are moved with the article into operative 45 relation with a driving wheel. The driving wheel contacting with a wheel secured to one of the prongs rotates the prongs and the article. The rapid rotation of the article causes the still pliable coating material to be distributed more uniformly over the surface of the article. While the article is being thus rotated a blast of air may be directed on it to assist the drying of the coating material. The coated article is delivered on to a 50 conveyor by means of which it is deposited in a delivery receptacle.

A machine of this type, suitable for coating golf balls, is illustrated in the accompanying drawings and described in detail below from which illustration and description a clearer understanding of my invention may be had.

In the drawings:

Figure 1 is a side elevation of the machine with the casing removed and with parts broken away;

Figure 2 is a sectional plan of the same taken along the line 2-2 of Figure 1;

Figure 3 is an end elevation of the same with the cover removed;

Figure 4 is a fragmentary plan; and

Figure 5 is a fragmentary, sectional elevation. Figures 6 and 10 show the coin control mechanism and associated structure.

Figure 7 is a sectional view on line 7-7 of Figure 6.

Figure 8 is a sectional view on line 8-8 of Figure 6.

Figure 9 is a section on line 8-9 of Figure 6.

Figure 11 shows in detail mechanism including means for synchronizing the delivery of a ball with means for operating coating mechanism.

Figure 12 is a section on line 12-12 of Figure 11.

The machine illustrated in the drawings is adapted to be controlled by a coin and may be set up at a golf club in some convenient place so that the members can relacquer their used golf balls. The entire machine with the exception of a hopper and a ball delivery receptacle is enclosed within a casing 1 which is secured to a base 2 on which the operating mechanism is mounted. The hopper 3 is a part of the receiver which in addition to the hopper includes a circular casing 4 mounted on the upper ends of two standards 5a and 5b. The block 4, which is provided with a series of apertures, six in number, each equal in diameter to the opening through the bottom of the hopper, is rotatably mounted on a spindle 6 extending from a plate 7 spanning the standards 5a and 5b. Before a ball can pass into the casing an aperture through the block must be brought into register with an aperture through the plate 7.

Operation of the machine and movement of the block or disk 4 into a position to permit the passage of a ball through the plate 7 is effected by inserting a coin 8 in the open end of a coin receiving chute 9. The coin in passing down the chute trips a switch 10 by moving a lever 11 and passes to a position shown in dotted lines between a pair of elements. The tripped switch closes a circuit to a driving motor 12 which is connected through a pulley 13 on one end of the motor shaft, a belt 14 and pulley 15a to a jack shaft 15 on which the pulley 15a is mounted. The jack shaft 15 is journaled in a pair of spaced bearing brackets 16a and 16b depending from the base 2. Intermediate the ends of the shaft 15, there is secured to the shaft a worm 15b, which meshes with a worm gear 17 secured on a shaft 18. Movement of the shaft 15 is transmitted to a shaft 19 through a pinion 20 mounted on the shaft 18 and a gear 21 mounted on the shaft 19 which is journaled in spaced bearing brackets 19a and 19b. On the shaft 19 there is mounted a cam 22 which is rotated with the shaft and which acts upon a cam follower 23 secured on a lever 24 intermediate the ends thereof. The lower end of the lever is rotatably secured to a standard 25 secured to the base 2. The upper end of the lever is pivotally secured to one end of a link 26. The other end of the

link 26 is secured to a driving bar 27 which is provided with an arm 27a that has a lateral end which extends into a longitudinal slot in a driven bar 28. The two bars are slidably mounted in a bracket 28a formed on an extension of the coin chute. It is between these two bars that the coin 8 comes to rest and it forms a connecting link between the bars without which the driving bar 27 moves under the action of the cam 22 and lever 24 without moving the driven bar 28. With the coin between the two bars, movement of the lever 24 to the left as shown in Figure 1, moves the driving bar 27 and through the coin, the driven bar 28 to the left. Such movement is transmitted through a bell crank lever 29 to a bar 30 slidably mounted in guides 30a and 30b on the plate 7 on which the block 4 rests. One arm 29a of the bell crank lever, which is mounted on a pivot 31 extending from the standard 5b, is connected to the driven bar 28 and the other arm 29b is connected through a link 32 to the slideable bar 30. The bar 30 carries a pawl 33 mounted on a pivot 34 which pawl cooperates with ratchet teeth 4a formed on the edge of the disk 4. The bar 30 is moved by the bell crank lever 29 an amount just sufficient to move the disk angularly through one-half the angular distance between the centers of successive apertures through the disk i. e. thirty degrees. This movement brings an aperture through the disk 30 into register with the opening through the plate 7 and permits a ball to pass through. The hopper 3 is out of alignment with the opening through the plate 7 an angular distance equal to the angle between successive apertures in the disk. By the movement of the disk under the action of the bar 30, a ball which passed into an opening in the disk in alignment with the hopper, is carried around by the aperture in the disk and moved into a position half way between the hopper and the opening through the plate 7. Return movement of the bar 27 is transmitted to the bar 28 through the lateral extension of the arm 27a.

The disk 4 is further rotated through an angle equal to half the angle between successive apertures to bring the ball holding aperture into alignment with the aperture through the plate 7 through a slideably mounted bar 35 mounted on the diametrically opposite side of the disk 7 to the position of the bar 30. The bar 35 carries a pawl 36 mounted on a pivot 37, and cooperating with the ratchet teeth 4a on the disk 4. Movement of the bar 35 is effected through a lever 37 the lower end of which is pivotally secured to a standard 38 mounted on the base 2. The upper end of the lever 37 is pivotally secured to a bracket 39 secured to the bar 35. Intermediate the ends of the lever 37, there is mounted on the lever a cam follower 40 which cooperates with a cam 41 for oscillating the lever, a spring holds the lever with the cam follower in contact with the cam.

The coin 8 inserted in the coin chute comes to rest between the driving and driven bars because it rests upon the periphery of a disk 42. The disk 42 is rotatably mounted on a shaft 43 extending between an extension of the bracket 28a and a bracket 44. Four pins 45 extend from the side of the disk and cooperate with a pawl 46 which rotates the disk 42. The pawl 46 is moved with the bars 27 and 28 and rotates the disk 42 which has a diametrical slot therethrough through which the coin may pass into a suitable receptacle not shown. In the machine shown, two balls are coated for a single coin.

This is accomplished because the bars 27 and 28 are reciprocated twice before the slot through the disk is brought into a vertical position so that the coin may fall from between the bars 5 27 and 28 and through the slot in the disk 42. Thus the disk 4 is rotated so that two balls are delivered into the machine before the link between the driving bar 27 and the driven bar 28 is removed.

10 When a ball passes through the block 4, it passes into a delivery chute 48 which is in alignment with the end of a dipping compartment 49a of a lacquer container 48. The walls of the dipping compartment, which is only slightly larger 15 in cross section than the ball, are arcuate so that the ball in being immersed moves along an arcuate path. The end of the compartment is closed by a cover 50 which is secured on a stud 51 rotatably mounted in a bracket 52 on the side of the container. The stud 51 extends 20 through the bracket and has a crank 53 formed on the end thereof. A tension spring 53c is secured between the pins 53a and 53b and midway between the open and closed positions of the cover traverses the axis of the stud. The spring 25 serves to snap the cover into the closed and open positions, the cover being moved slightly past the midway position of the spring as hereinafter described. The cover is of course opened 30 each time a ball enters the chute 48. The cover is moved to open and close the dipping compartment in timed relation with the action of the feeding disk 4 through the movements of a shaft 55 to which it is connected by a crank 56 mounted 35 on the shaft and a link 57, the ends of which are connected to the crank and the cover 50. The end of the link connected to the cover is slotted and receives a pin 57a which extends into the cover. The slot allows the snap action of 40 the cover when it is moved to a position in which the spring 53 passes its center position.

The shaft 55, which passes through and is journaled in the side walls of a recess formed in the top of the lacquer container, is oscillated 45 through a crank, link, lever and cam connection to the shaft 19. On the shaft 55 there is mounted a crank 58 which is pivotally secured to one end of a link 59, the other end of which link is pivotally secured to one end of a lever 60. The 50 lever 60 is mounted to rock on a pivot 60a secured in the standard 5b. The opposite end of the lever 60 is pivotally connected to a link 61 which is also connected to a slide 62 carrying an arm 62a. The slide 62 is slidably mounted upon 55 a vertical lever 63 which is pivotally secured at its lower end to the standard 5b. This lever carries the arm 62a of the slide into and out of a position in which the arm lies in the path of a pin 64 mounted on the side of a disk 65 rotatably mounted on the shaft 19. The action of gravity acting on the several parts of this train normally maintains the slide 62 in its uppermost position from which position it is moved downwardly by the pin 64 to oscillate the lever 60 and 60 thus the shaft 55. Normally, the lever 63 is held, by engaging a shoulder 66a on a horizontal lever 66, in a position in which the arm 62a is withdrawn from the path of the pin 64. The lever 66 is pivotally secured to a bracket 67 depending from the plate 1. One end of the lever 66 cooperates with one arm of another pivotally mounted lever 68, the other arm of which extends into the ball chute 48. As a ball passes 65 through the chute it moves the lever 68 about its pivot; and the end of the lever 68 cooperating

with the lever 63 is depressed. The opposite end of the lever 66 is raised and the end of the lever 68 is released. When released, the lever 68 is moved to the right as seen in Fig. 1 by a spring 69 and carries the arm 62a of the slide 62 into the path of the pin 64. The lever 68 is returned to its initial position through an overhanging arm 62b secured to the slide 62. When the arm 62a is in position to engage the pin 64, the arm 62b contacts with the periphery of the disk 65 10 and downward movement of the slide forces the arm, slide and lever 68 to the left as seen in Fig. 1. As the end of the lever 68 passes the shoulder 66a of the lever 66, a spring 70 moves the lever 66 so that the shoulder 66a engages 15 the lever 68. In this position, the arm 62a of the slide is moved out of the path of the pin 64.

A ball immersed in the dipping compartment is removed therefrom by an arm 71 mounted in the lacquer container and secured to the shaft 55. 20 The arm 71 has a pronged end 71a which engages a ball in the dipping compartment and raises the ball out of the compartment when the shaft 55 is oscillated, the cover 50 being moved to permit the ball to pass. The arm 71 is secured to the shaft 55 25 to rotate therewith through a pin 72 which acts in a slot in the hub 71b of the arm 71. This lost motion connection affords time for the ball to be immersed after the cover is opened. Since the arm is mounted in the lacquer container and is 30 only exposed for a fraction of a minute for each ball that is immersed, it cannot become coated as any lacquer on it does not have a chance to dry.

When a ball is lifted out of the dipping compartment by the arm 71 it is gripped between two 35 prongs 73a and 73b, and rotated. Each of the prongs is formed on a shaft that is journaled in a bearing, the prong 73a being mounted on the end of a shaft 74 journaled in a bearing 75 and the prong 73b being mounted on the end of a shaft 40 76 journaled in a bearing 77. The bearings 75 and 77 are formed on corresponding ends of levers 78 and 79 respectively. The levers 78 and 79 are pivotally mounted, between their ends on opposite sides of a slide plate 80, the lever 78 being 45 mounted on a pivot 81 and the lever 79 being mounted on a pivot 82. The slide plate 80 has a tongue on each side which is slidably mounted in a groove formed in a supporting plate 83 on which the slide 80 is slidably mounted. The ends of the 50 levers 78 and 79 opposite the ends on which the bearings are mounted are connected by pivotally secured links 84 and 85 respectively to a bracket 86 formed on the end of a guide bar 87 slidably mounted between two overhanging guide plates 88 55 and 89 mounted on, longitudinally and centrally of the slide 80. A bifurcated arm of the bracket 86 is pivotally secured to one end of a lever 90, the other end of which is pivotally secured to a standard 91 mounted on the base 2. Intermediate the ends of the lever 90 there is secured to the lever a cam follower 92 which cooperates with a cam 93 mounted on the shaft 19. As the cam 93 rotates, the lever 90 oscillates about its pivotal connection to the standard 91. As shown in the 60 drawings, the lever 90 is in a position of rest at which the prongs 73a and 73b and the golf ball A therebetween are rotated. This rotation is accomplished through the contact of a friction wheel 94 mounted on the end of the shaft 74 and a drive wheel 95 mounted on a shaft 96 which is connected to be rotated by the gear 17 through a pinion 97 secured to the shaft 96 and meshing with the gear 17. After the ball has been rotated 65 sufficiently to distribute the lacquer over the sur- 75

face thereof and the lacquer is practically dried thereon, the upper end of the lever 98 moves in the direction of the lacquer container and moves the slide 88 until the ball between the prongs is suspended directly over a runway 88. The upper end of the lever 98 is then moved in the opposite direction which action draws together the ends of the levers connected to the links 84 and 85 and separates the ends of the levers carrying the bearings 75 and 77. The ball is thus released from the prongs 73a and 73b and drops on the runway 88 along which it moves to a conveyor 99. The lever 98 continues to move in this direction until the prongs 73 are over the opening to the dipping chamber. Movement of the upper end of the lever in the reverse direction acts through the links 84 and 85 to move the prongs 73 together. This movement takes place when a ball is lifted out of the dipping compartment by the arm 71. The ball is thus gripped between the prongs and is moved by continued movement of the lever 98 to the position shown in the drawings.

The drying of the lacquer on the ball is assisted by a blast of air from an air pipe 108. Air under pressure is supplied to the pipe 108 by a rotary compressor 101 connected to the shaft of the motor 12.

A ball deposited on the runway 88 rolls on to the conveyor 99. The conveyor 99 is of the chain type and is mounted on a pair of sprockets 102 and 103 mounted on shafts 104 and 105 journaled in spaced standards 106 and 107 respectively. The sprocket 102 is secured to the shaft 104 to which there is also secured a ratchet wheel 108. One end of a lever 109 is rotatably mounted on the shaft 104 and the lever carries a pawl 110 which cooperates with the ratchet wheel 108. The other end of the lever 109 is secured to one end of a link 111, the other end of which link is secured to the upper end of a lever 112. The lower end of the lever 112 is pivotally connected to a standard 113 mounted on the base 2. A cam follower 114 mounted intermediate the ends of the lever 112 engages a cam 115 mounted on the shaft 109 and adapted to oscillate the lever 112 which is held against the cam by a spring 116. Through this motion transmitting train the conveyor is operated to deliver a ball thereon to another runway 117 which terminates in a delivery receptacle 118 which protrudes from the outer surface of the casing 1.

The switch 10 is normally held in an open position by a leaf spring 10a acting on an arm 10b of the switch. When tripped by a coin contacts 10c and 10d are brought together and a circuit closed to the motor. The switch is held in the closed position through the action of a lever 119 cooperating with an arm 10e of the switch. The lever 119 is pivoted between its ends on a pin 120 and carries a pin 119a at its upper end which engages the arm 10e of the switch. The lever is urged towards the arm by a spring 121. In the open position of the switch, the pin 119a abuts against the end of the arm 10e. When however, the switch is tripped and the arm 10e raised, the pin 119a moves to a position under the arm 10e as shown and prevents the switch from returning to its original position. After the machine has operated to lacquer and deliver two balls, the lever 119 is swung about its pivot to release the switch 10. This is accomplished by a pin 122 secured to the sprocket 102 and cooperating with the lower end of the lever 119. As the pin 122 moves around with the sprocket, it engages the lower end of the lever 119 and swings the lever

about its pivot to its initial position in which position the switch is released. When the pin 122 and lever 119 become disengaged, the pin 119a abuts against the end of the arm 10e.

Where ever a cam follower and cam cooperate in this machine, a spring is used to maintain the cam follower in contact with the cam. To simplify the drawings, some of these springs have not been shown but it will be appreciated that each such spring is connected at one end to the movable element carrying the cam follower and at the other end to the base or some element fixed with respect to the base.

It is obvious that various changes may be made by those skilled in the art in the details of the embodiment of the invention illustrated in the drawings and described in detail above within the principle and scope of my invention as expressed in the appended claims.

We claim:

1. In a machine for coating the entire surface of articles with a lacquer, the combination comprising a conveyor arm having an article supporting end portion mounted for movement in a vertical plane, article delivering mechanism having an article delivery opening containing the plane of movement of the conveyor arm, a lacquer container positioned to contain the plane of movement of the conveyor arm, and means for operating the conveyor arm between a position in which the article supporting end portion is directly beneath the delivery opening of the article delivery mechanism and a position in which the article supporting end portion is wholly within the lacquer container.

2. In a machine for coating the entire surface of articles with a lacquer, the combination comprising a conveyor arm having an article supporting portion mounted for movement in a vertical plane, article delivering mechanism having an article delivery opening containing the plane of movement of the conveyor arm, a lacquer container positioned to contain the plane of movement of the conveyor arm, means for operating the conveyor arm between a position in which the article supporting portion is directly beneath the delivery opening of the article delivery mechanism and a position in which the article supporting portion is wholly within the lacquer container.

3. In a machine for coating the entire surface of articles with a lacquer, the combination comprising a pair of pivotally mounted levers slidably mounted for conjoint movement transversely to the path of movement of the conveyor arm, gripping jaws rotatably mounted on said levers, means for moving the gripping jaws transversely to the path of movement of the conveyor arm, means for causing the jaws to contract and grip an article supported by the conveyor, and means for rotating the gripping jaws in one extreme position of their movement transversely to the path of movement of the conveyor arm.

3. In a machine for coating the entire surface of articles with a lacquer, the combination comprising a lacquer container, article delivery mechanism having an article delivery opening directly above the opening to the lacquer container, a conveyor for the articles to be lacquered comprising an arcuate arm mounted within the lacquer container and an end portion having point supports for supporting an article to be lacquered, and means for oscillating the conveyor arm between a point in which the end portion thereof is outside of the lacquer container and directly beneath the delivery opening of the delivery mech-

anism and a point in which the end portion thereof and an article thereon are wholly within the lacquer container.

4. In a machine for coating the entire surface of articles with a lacquer, the combination comprising a lacquer container, a conveyor arm mounted upon a shaft for oscillatory movement within the container, the conveyor arm including a section extending radially of its axis of oscillation, an arcuate section extending from the radial section and having its center of curvature at the axis of oscillation of the arm and point supports on the free end of the arm for supporting an article thereon, and means for oscillating the arm between a position in which the free end thereof and an article thereon will be wholly immersed in the lacquer in the container and a position in which an article supported on the free end of the conveyor arm is wholly outside of the container.

5. In a machine for coating the entire surface of articles with a lacquer, the combination comprising a conveyor arm having an article-sup-

porting end portion mounted for movement in a vertical plane, article delivering mechanism having an article delivery opening containing the plane of movement of the conveyor arm, a lacquer container positioned to contain the plane of movement of the conveyor arm, and means for operating the conveyor arm between a position in which the article-supporting end portion is directly beneath the delivery opening of the article delivering mechanism and a position in which the article-supporting end portion is wholly within the lacquer container including a pivotally mounted lever, means connecting one end of the lever for actuating the conveyor arm, a pivotally mounted bar, a block slidably mounted on the bar, a link connecting the block and the lever, a rotatably mounted disk, a pin on said disk for engaging said block, and an abutment on said block to engage the edge of the disk upon movement of the block.

MAYNARD F. HOLT.
SIGMUND N. LIPOWSKI.
